UNITED STATES PATENT OFFICE.

THOMAS GREGORY, OF SOUTHPORT, ENGLAND.

REGISTERING AND RECORDING APPARATUS FOR TRAM-CARS AND OMNIBUSES.

SPECIFICATION forming part of Letters Patent No. 444,883, dated January 20, 1891.

Original application filed November 4, 1889, serial No. 329,252. Divided and this application filed July 22, 1890. Serial No. 359,553. (No model.) Patented in England October 30, 1888, No. 15,596.

To all whom it may concern:

Be it known that I, THOMAS GREGORY, a subject of the Queen of Great Britain, residing at Southport, England, have invented new and useful Improvements in Self Registering and Checking Apparatus for Tram-Cars and Omnibuses and Like Purposes, (for which I have obtained a patent in Great Britain, No. 15,596, bearing date October 30, 1888,) of which the following is a specification, this being a division of application No. 329,252, filed November 4, 1889.

The improvements relate to self registering and checking apparatus for tram-cars and omnibuses and like purposes, and have for object the automatic registration and recording or checking of the number of passengers traveling and also the distances traveled in such like vehicles. To effect this and to accomplish my improvements I by preference construct the steps leading to the roof of the car and the platform conducting to the interior in such manner that they may be capable of being depressed by the weight of a passenger. These depressible steps are fitted with suitable levers or attachments and link or other connections, which enable them to actuate (on the depression thereof) a ratchet-and-pawl motion attached to or driving a drum or pulley; or it may be more than one, carrying a ribbon or a tape of paper or suitable substitute, on which are printed or otherwise marked consecutive numbers. By preference one of these numbers always comes opposite to a slot or opening in the box or casting of the apparatus, so as to be exposed to view, and thus each time the complete motion is given to the depressible step the next following number is brought opposite the slot, and thus this portion of my improvements indicates how many persons or passengers have entered the vehicle.

For the purpose of registering and recording the distance traveled I employ in addition to the foregoing a disk and pointer and also stampers, which disk and stampers are of various colors or devices. The disk, or it may be the pointer, has revolving motion given thereto by means of a lever operating a ratchet and train of wheels, which lever takes its motion from one of the wheels or

axles of the vehicle, and thus enables a continuous measure of the distances traveled to be indicated on such disk. These distances, or it may be only the desired stages of the journey, are indicated on the disk or dial by dividing the same into colored or otherwise marked spaces corresponding with the distances of the stages. To produce a record of these distances I employ an arrangement of stampers of colors or devices or markings, one to correspond with each stage or distance as shown on the dial. These stampers are consecutively brought into juxtaposition with the ribbon or tape of paper as the different stages are reached, and as they are brought into gear they are actuated in turn by the depression of the steps, and thus show the particular stage at which the passengers enter the vehicle. These colored or other stampers may be fixed on a sliding rod and drawn into position by means of lever and link or other connections by a suitably-formed cam cut to the requisite stages and placed either behind the dial aforesaid or otherwise, and may be actuated by the same means. To complete this record, when such is necessary, I cause the stampers to again act on the same or other ribbons when the passengers come out of or down from the vehicle, thereby showing at what stage exit as well as entrance was made, thus showing the distance traveled; but where this is not required the stamping operation may be caused to act in one direction only, as will be readily understood. For the purpose of satisfying the passengers and preventing disputes with the guard, I may provide tickets bearing the same color or device as that indicated on the dial and stamper operating at the moment of entrance, so that on comparing the ticket with the dial on exit the proper fare can be accurately determined. To enable children to pass into the vehicle without recording, I prefer to employ with the depressible steps a counter-balance, so that when a child steps on the platform under the weight at which such counter-balance is set to act the step will not be depressed and the record will not take place. The dial or disk or other traveling ribbon or other moving or fixed parts of the apparatus may or may not be employed partly for advertising purposes;

but that the improvements may be better understood I will, with the aid of the accompanying drawings, proceed more fully to describe means employed by me.

5 In the drawings, Figure 1 shows a front elevation, and Fig. 2 a side view, of portions of checking and registering apparatus arranged in accordance with my invention. Fig. 3 shows a longitudinal section of a portion of 10 the staircase of a car, and Fig. 4 a plan view thereof, while Fig. 5 shows an arrangement of apparatus employed in actuating the registering dial or pointer.

The same letters indicate corresponding 15 parts wherever they occur.

20 *a a' a'* are sets of geared-roller apparatus for carrying and moving forward the ribbons of paper or substitute therefor on which the registration and checking of the passengers 25 are recorded. These ribbons or strips may or may not be provided with consecutive numbers thereon; but I prefer they should so be prepared.

Motion is given to the ribbon-roller *a a* and 25 *a' a'* by means of ratchet-and-pawl gear through the terminal-rods *w w* and *w' w'* in manner to be hereinafter described.

30 *c c* is the slide, carrying the stampers *d d* and *d' d'*. As any stamper comes opposite the bent levers *f f' f' f* it is caused to stamp the ribbon of paper.

35 *g g* is the revolving disk, which can be marked into stages of the journey by colors or devices; and *h h* is the notched wheel or 40 cam cut to correspond with such stages.

These are driven through the operation of suitable toothed wheel or other gearing by 45 means of the pawl-and-ratchet motion *j j*, operated by the pin or sliding rod *k k*, which is lifted each time the wheel of the car makes a revolution by means of the projection *l l* on the axle and intervening lever *m m*. The stop *u u*, attached to the slide *c c*, bearing against the cam *h h* by pressure from the 50 spring *o o*, keeps the first of the stampers *d d* and *d' d'* opposite the bent levers *f f* and *f' f'* until by traveling the distance of a stage of the journey the spring is allowed by the fall in the cam to force the second stamper into gear, and so on as each stage is reached.

Although four stages and stampers are shown, more or less than that number may be employed, according to the number of stages desired. As each stamper is provided with 55 a different color or device, by preference to correspond with the color or device on the

disk, a record is kept, showing at what stage a passenger enters or makes his exit.

The stampers *d d* and *d' d'* are actuated by the outside passengers by means of movable steps *b b*, leading to the roof of the car. Two steps are rendered operative on passengers going up to record their getting on the car, while two other steps are operative in recording their coming down again. Any 60 steps may be used, and I prefer to make the whole of the steps movable and changeable in operation, so that neither passengers nor guard may know which steps for the time being are utilized. The steps are connected 65 with levers *s s* and links *t t* to the terminal rods *v v v' v' w w w' w'*. The first step operates the rod *w' w'*, and by this the ratchet-and-pawl motion, thus drawing the ribbon forward one number or space, and at the same 70 time allows the small disk or guard *x x* at the end of the lever *x' x'* to uncover the paper for the stamping process, which the second step effects by operating the rod *v'* and the lever *f'*. The third step actuates in like manner 75 the stamping-rod *v* and lever *f*, but as the guard-plate or disk is not first removed there is no mark produced upon the paper, which is simply ratcheted on without stamping by depression of the fourth step. On the passenger coming down the operation is reversed and the second ribbon is stamped, while the 80 first is guarded. Similar apparatus may be employed for inside passengers by using a 85 duplicate set of stampers on the same or a 90 second ribbon.

y y is a ratchet or star wheel for registering the number of times the sliding bar is put back, thus showing the journeys made and forming a check against attempts at fraud on 95 the part of the guard or attendant.

The improvements and modifications thereof are applicable to other and analogous entrances than those of tram-cars.

Having now particularly described and ascertained the nature of my said invention, and in what manner the same is to be performed, I declare that what I claim is—

In registering and recording apparatus, the combination of stampers *d d* and *d' d'*, the sliding bar *c c*, and the covering disks *x x*, which stampers *d d* and *d' d'* are respectively operated substantially as herein set forth.

THOMAS GREGORY.
